UNITED STATES PATENT OFFICE.

FREDERICK QUEDNOW, OF CLEMENTON, NEW JERSEY.

STAMP-AFFIXER.

SPECIFICATION forming part of Letters Patent No. 606,791, dated July 5, 1898.

Application filed November 29, 1897. Serial No. 660,089. (No model.)

To all whom it may concern:

Be it known that I, FREDERICK QUEDNOW, a citizen of the United States, residing at Clementon, in the county of Camden, State 5 of New Jersey, have invented a new and useful Improvement in Stamp-Affixers, which improvement is fully set forth in the following specification and accompanying drawings.

My invention consists of a device for affixing 10 stamps to envelops, papers, &c., the same embodying a box containing stamps and from which stamps may be removed from the bottom thereof, a plunger having a head movable within said box for creating pressure on 15 the stamps, and a flap which is adapted to be presented to a piece of sponge or other absorbent material on the base of the device and then contact with the envelop or paper, so as to wet or moisten the same preparatory 20 to the full extent of descent of the plunger when the stamp is pressed against the wet or moistened surface, whereby when the plunger rises the stamp is withdrawn from the box, while adhering to the envelop or paper, 25 the parts of the device then returning to their normal position, the construction and operation of the device being hereinafter more fully set forth, and the novel features pointed out in the claims that follow the specification.

Figure 1 represents a perspective view of 30 a stamp-affixer embodying my invention. Fig. 2 represents a longitudinal vertical section thereof.

Similar letters of reference indicate corresponding parts in the figures.

Referring to the drawings, A designates the base of the device, the same being hollow and adapted to contain water or other suitable fluid for moistening stamps. In the upper 40 face of said base is the opening B, which is occupied by the frame C, within which is the piece C' of sponge or other absorbent material, which latter dips into the fluid in said base A.

Rising from the base is the elbow D, on 45 whose upper limb are bosses E E', in which is guided the plunger F, the latter being pressed upwardly by a suitable spring and carrying the cross-head G, which is adapted to move 50 along the vertical plate H, which connects said bosses, thus preventing rotation or turning of the plunger. The ends of said cross-

head have thereon projections J, which latter are adapted to ride upon the angular arms K, whose upper ends are pivotally connected 55 with the boss E and formed with shoulders K', against which the projections J bear when the plunger is depressed, said arms being deflected in angular form, so that when said arms are advanced by the pressure of the 60 projections on said shoulders K' said projections ride down along the right-line portion K² of said arms and prevent the return of the arms during the subsequent descent of the 65 plunger. The lower ends of the arms are connected by the bar K³, the same carrying the pad L, which when in normal position contacts with the upper end of the sponge or absorbent material C'.

The lower end of the plunger passes freely 70 through the top M of the box N and has connected with it the presser-head P, which, owing to the spring Q, which bears against said top and a shoulder on said plunger, causes the normal position of said head to be at the 75 upper portion of said box, but when the plunger is lowered the head is depressed against the stamp in the box, the latter being open on its bottom, where it is provided with the lips R, which project inwardly and serve to 80 prevent the dropping of stamps from said box.

On the base A is the stop S, to which is secured the fingers T, which project forwardly from said stop above the base A, parallel with the long sides of said base, a space existing 85 between said fingers and the upper side of the base for the insertion of the envelop, said fingers constituting guides to prevent the ascent of the envelop when the plunger rises and also serving to properly locate the en- 90 velop at the stamp-corner below the box N.

In order to remove the box, the body of the same is formed separate from the top M, and the latter is provided with studs U and V, which project horizontally therefrom, the 95 studs V entering openings in one side of the body of the box and the stud U receiving the spring-catch W, which is connected with the opposite side of the box, thus suspending the body from the top and permitting of the removal of said body when said catch is drawn forward, the body then being detached.

The operation is as follows: The base is supplied with water and the box with stamps,

the gummed sides of the latter being down. An envelop, &c., is then placed on the base beneath the box, the stamp-corner being above. The plunger is now depressed, and 5 as the pad L has been in contact with the top of the sponge or absorbent piece said pad is moistened or wet, and as the projections J press against the shoulders of the arms K the latter are moved forwardly and the pad L is 10 carried quickly under the box in contact with the adjacent portion of the envelop, &c., whereby said portion is supplied with water and made moist, and as the plunger continues its descent the bottom of the box contacts 15 with the envelop as a stop. The head P within the box descends to some extent under the action of the plunger, and so exerts pressure upon the pile of stamps, so that the lowermost stamp is pressed firmly against the wet 20 or moistened surface of the envelop, &c., thus causing the stamp to adhere to the envelop, &c. The plunger is now let go, whereby it rises, and both the head and box move therewith independent of each other. Now as the 25 stamp has adhered to the envelop, &c., it is drawn out from the box, and the bottom of the latter presents another stamp. Meanwhile the pad L, which had been advanced to the front of the box and above the envelop, 30 &c., returns under said box to its normal position and again contacts with the sponge or absorbent material C', limited in its rearward motion by the elevated back X of the frame C, against which the bar or carrier K³ of the 35 pad L strikes, it being noticed that said arms are drawn rearwardly by the spring Y, which is connected with the same and a proper portion of the elbow D. The pad depends from the carrier K³ and projects downwardly, and 40 as the arms describe their circular motion said pad after being moistened and advancing is so gaged that should the base be unoccupied it will not be wet or moistened; but when an envelop, &c., is upon said base it alone 45 will be contacted by said pad, it being also noticed that the pad moves under the box without contacting with the bottom of the box or stamps.

Having thus described my invention, what 50 I claim as new, and desire to secure by Letters Patent, is—

1. A spring-actuated plunger and bearings therefor, a transverse cross-head on said plunger having lateral projections, a pair of arms 55 on opposite sides of the plunger with which the said projections engage, a guide on which said cross-head has sliding movement, a pad carried by the lower ends of said arms, a hollow base directly under said plunger, a box 60 carried by the lower end of said plunger, and

a piece of absorbent material in said base and partly rising therefrom, said pad being adapted to contact with said piece, and to pass under said box and contact with the face of an envelop, &c. supported on the base. 65

2. A base having an unyielding pressure-surface and adapted to contain fluid, a piece of absorbent material adapted to dip into said base, a frame on the base for supporting the said piece, the back of said frame rising above 70 said piece as a stop, a spring-controlled plunger mounted in bearings, a stamp-receptacle carried by and movable with said plunger, swinging arms mounted on the bearings of 75 said plunger, a downwardly-projecting pad on the lower ends of said arms, and a cross-head on the plunger adapted to engage and operate said arms, said arms being movable 80 between the stamp-receptacle and said base, and adapted to contact in normal position with said piece, and when in operation to pass over the base in contact with the face of an envelop, &c. thereon.

3. A base adapted to contain a fluid, and a piece of absorbent material dipping thereinto, an elbow rising from said base, a vertical plate connected with said elbow, a boss on said plate, a spring-pressed plunger in said boss, a stamp-receiving box having its top freely carried by said plunger, a movable 85 head in said box, connected with said plunger, a deflected arm mounted on said boss and having a shoulder on its upper end, a cross-head on said plunger adapted to engage 90 with said shoulder, and ride along the right-lined portion of said arm, a pad carried by the lower end of said arm, and projecting downwardly adapted to contact with said absorbent material, and sweep over said base, a 95 spring connected with said arm for returning the same to its normal position and yielding fingers on said base elevated above the 100 same.

4. In a stamp-affixer, the combination of a rigid hollow base having a moistening-piece 105 rising therefrom, a guide supported by said base, a plunger mounted in said guide and having a cross-head secured thereto provided with outwardly-projecting projections, a pair 110 of spring-actuated arms pivotally attached at their upper ends to the guide and carrying a pad at their lower ends, said projections bearing upon the arms and operating them when the plunger is depressed, and a stamp-box supported solely by and movable with 115 the plunger.

FREDERICK QUEDNOW.
